(57) **CLAIM**

The ornamental design for a portion of a shoe upper, as shown and described.

DESCRIPTION

FIG. 1 is a front perspective view of a portion of a shoe upper showing my new design;

FIG. 2 is a side view thereof;

FIG. 3 is a top view thereof;

FIG. 4 is a front view thereof; and,

FIG. 5 is a rear perspective view thereof.

The broken line eyelets in the figures represent an unclaimed portion of the design. The uneven broken line bounding the shaded area of the design in the figures represents an unclaimed boundary of the design. The heavy even broken lines in the figures represent stitching. The uneven broken line showing of the remainder of the shoe is for illustrative purposes only and forms no part of the claimed design.
